10 Claims. (Cl. 57—34.5)

1 This invention relates to improvements in textile machinery and more particularly to improved devices on spinning frames for removal of dust, fluff, broken thread ends and the like.

The general object of the invention is to arrange for reciprocating movement of a series of nozzles so that the quantity of air handled for the production of desired suction effect may be varied; and effective operation assured despite the employment of small quantities of air.

Devices on spinning frames are known in which the thread guide eyelets of the yarn feed motion are moved backwards and forwards in the axial direction of the draw frame rollers, and in which nozzles for the removal by pneumatic suction of dust, fluff, broken thread ends and the like are fitted between the draw frames and the spindles. Such devices are known as end breakage suction exhausters. Since, however, the yarn leaving the draw frame constantly changes its position as a result of the reciprocating motion of the yarn guide eyelets of the yarn feed motion, the nozzles—if stationary—must be provided with relatively wide mouths to prevent the yarn from moving beyond the range of the nozzle suction. The cross-sectional areas of the air ducts and the power of pneumatic installation, and consequently the initial and operating cost of the same, thus becomes very high because of the relatively large cross-sectional areas of the nozzles. Even so, the second main purpose of the yarn breakage suction exhauster, namely, the continuous removal from the draw frame rollers on the delivery side of dust and fluff beyond the stretch travelled over by the yarn in its reciprocating motion is not achieved at all or is only achieved to a very inadequate degree.

These drawbacks can be overcome by the present invention in that, in addition to the machine cross-member, for the reciprocating actuation of the yarn guide eyelets, at least one other machine cross-member is provided which imparts a reciprocating movement to the nozzles. It is particularly desirable in this connection so to provide the means for the simultaneous drive and control of the machine cross-members that the reciprocating movement of the nozzles follows a cycle or rhythm differing from that of the reciprocating motion of the yarn guide eyelets, the cycles used being timed in relation to each other. Investigations have disclosed the fact that differences exist between the reciprocating movement of the yarn guide eyelets and the change in position of the yarn on the delivery side of the draw frame thereby achieved. These dif-

2 ferences may, according to the design of the particular spinning frame, assume substantial proportions.

Through the fact that the cycle of the reciprocating movement of the nozzles is, to allow for these differences, so selected as to differ from the cycle of the reciprocating movement of the yarn guide eyelets, it is possible, without detriment to the effectiveness of the nozzles, to arrange for the nozzle apertures, and consequently the necessary quantity of air handled by the pneumatic installation, to be kept extremely small.

Figure 1 is a diagrammatic view of a spinning machine embodying the present invention;

Figure 2 is a view in elevation of a portion of a spinning machine including a modification of the present invention;

Figure 3 is a plan view of a portion of the machine shown in Figure 2;

Figure 4 is a view in elevation of a further modification; and

Figure 5 is a plan view of a portion of the machine shown in Figure 4.

25 In the embodiment shown in Fig. 1 a spinning machine with a two-unit draw frame is shown. Each draw frame unit comprises four nip rollers per thread of yarn filament, namely, the fluted roller 1 on the intake side with its top roller 2, and on the delivery side the fluted roller 3 with its top roller 4. The fluted intake rollers 1 of the various drawing frames are mounted on a driven shaft 5 and, correspondingly, the fluted delivery rollers 3 are mounted on another driven shaft 6. The roving paid out by the roving bobbins 7 is drawn into the draw frames by the fluted intake rollers 3; the roving is there drawn and the yarn so obtained is finally taken up by the driven spindles 11. The roving is in this process led, before reaching the draw frames, through yarn guide eyelets 9 and the finished yarn is led, before reaching the spindles, through yarn guide lappets 10.

The yarn guide eyelets 9 are moved to and fro, by means of the yarn feed motion, parallel to the axes of the draw frame rollers 1 to 4. To this end the yarn guide eyelets 9 are arranged on a machine cross-member 12 displaceable along its longitudinal axis, which cross-member may for instance be moved reciprocatingly by a crank pin 14 through a rod 13. The crank pin 14 of the yarn feed motion may be driven by a shaft 16 of the spinning frame through a suitable intermediate gear shown in Fig. 1 as an ordinary intermediate gearwheel 15. The reciprocating mo-

tion of the yarn guide eyelets 9 moves the roving yarn 8 in the axial direction of the draw frame rollers and thereby prevents the wearing of undesirable grooves in the rollers of the draw frame. The position indicated by a dotted line of the crank pin 14', the rod 13' and the yarn guide eyelets 9' produces the course 8', shown by dotted lines, of the yarn through the spinning frame. The actuating devices for the draw frames, for the spindles 11 and for the shaft 16 of the yarn feed motion are omitted to avoid confusion in the drawing.

Between the fluted delivery rollers 3 of the draw frames and the yarn guide lappets 10, nozzles 17 of a pneumatic installation are arranged. These nozzles may consist of simple and preferably slot-shaped apertures in a collecting duct 18, which is connected by an articulated member 19 to the fan 20. The pneumatic installation is so designed that the fan 20 sucks in air from the nozzles 17 in the direction shown by the arrows in the drawing. Dust, fluff, broken yarn-ends and the like are drawn in by the nozzles 17 and the particles so removed are collected in the separator 19.

Contrary to what is the case with the known devices, a further machine cross-member is provided the sole purpose of which is to cause the reciprocating motion of the nozzles 17. This machine cross-member may, as already indicated in Fig. 1, be the collecting duct 18 itself on which the nozzles 17 are mounted. The collecting duct 18 is for this purpose so designed as to be displaceable in its longitudinal direction, and is moved to and fro through a system of rods 21, 22 by a crank pin 23. Said crank pin 23 is driven from the shaft 16 through an intermediate gearwheel 24 or through an intermediate gearing, in such a manner that the two crank pins 14 and 23 respectively rotate at the same speed in the same direction.

The collecting duct 18 with the nozzles 17 is controlled and moved to and fro out of synchronism with the yarn guide eyelets 9. The cycle of motion of said collecting duct 18 with the nozzles 17 may differ simply in the fact that the amplitude of the reciprocating movement of the nozzles 17 is smaller than that of the reciprocating movement of the yarn guide eyelets 9. The more numerous the pairs of rollers possessed by the draw frame, the smaller must be the amplitude of the reciprocating movement of the nozzles, so that the yarn filaments are at all times within the range thereof. The position shown by a dotted line of the yarn filament 8', the nozzles 17' and the collecting duct 18', the rod system 22' and the crank pin 23' illustrates these circumstances. But even if the draw frame comprises two pairs of rollers only, the necessary amplitude of movement of the nozzles 17 is smaller than that of the yarn guide eyelets 9, because the yarn filaments, on account of the rigidly mounted yarn guide lappet 10, are displaced less far on the delivery rollers 3 than on the intake rollers 1 of the draw frame. For these reasons it is desirable to provide a device by means of which the amplitude of the reciprocating movement of the nozzles is adjustable in relation to that of the reciprocating movement of the yarn guide eyelets. Such a device may, in its simplest form, consist in an arrangement whereby the pivot pin by means of which the system of rods 22 is articulated to the crank pin 23 can be displaced radially. This adjustability is indicated

in the drawing by the slot 29 radially provided in the crank pin 23.

If the speed of the reciprocating movement of the yarn guide eyelets is not minute in relation to the speed at which the roving enters the draw frame, the yarn leaving the draw frame lags behind the reciprocating movement. The nozzles 17 in such case are controlled to follow a cycle lagging behind that of the yarn guide eyelets 9. If the distance-time curve of the reciprocating movement of the yarn guide eyelets is sinusoidal, the corresponding distance-time diagram is, as a first approximation, a phase-shifted sinusoidal curve of lesser amplitude in accordance with which the nozzles 17 should be moved to and fro. Preferably, therefore, suitable means are provided by which the phase position of the reciprocating movement of the nozzles is adjustable in relation to that of the reciprocating movement of the yarn guide eyelets. In Fig. 1, for example, such an adjustment of the phase may be effected by temporarily removing the intermediate gearwheel 24, off-setting the crank pin 14 with the shaft 16 in relation to the crank pin 23 by the desired phase angle, and then replacing the intermediate gearwheel 24.

If, on the other hand, the reciprocating movement of the yarn guide eyelets 9 does not follow a sinusoidal course, the cycle of the reciprocating movement of the nozzles coincides with that of the yarn guide eyelets only as regards the periodic duration of the reciprocating motion, whilst within the period the nozzles may be controlled to a cycle the time curve of which deviates completely from that of the yarn guide eyelets. If, for example, the distance-time curve of the reciprocating movement of the yarn guide eyelets 9 is a zig-zag curve consisting of straight lines, then the nozzles may be controlled in accordance with a cycle derived from a sine curve distorted by uneven harmonics, the zero points (origins) of the distorted sine curve being out of synchronism with the zero points of the zig-zag curve in that they lag behind the latter, and the amplitude of the distorted sine curve being less than that of the zig-zag curve.

The separate control of the yarn guide eyelets and nozzles respectively by means of different machine cross-members thus makes it possible, even in the case of reciprocating motions at more substantial speeds, for the yarn filaments to remain at all times within the range of the nozzle suction. Sufficient exactness is almost always achieved when, as in Fig. 1, merely the amplitude and phase of the reciprocating movement of the nozzles are correctly set.

In order to achieve at the same time the most thorough possible cleaning of the draw frame rollers under conditions of minimum air consumption it may be found advantageous purposely to produce small divergences between the movement of the nozzles and the changes in position of the yarn filaments. If, for instance, by means of the nozzles, the fluted delivery rollers are at the same time to be kept clean beyond the distance covered by the yarn in its reciprocating sweep, it is advantageous to impart to the reciprocating movement of the nozzles an amplitude of movement greater than that of the yarn. In the case also of the recently-adopted cyclic control of the yarn guide eyelets in which a rapid reciprocating movement of small amplitude is superimposed upon a slow reciprocating movement of large amplitude, it may prove expedient to follow only approximately with the nozzles. It

is then frequently sufficient for the nozzles to follow only the slow reciprocating movement at the correct amplitude and phase and not to participate in the rapid reciprocating movement. In the present example of roller cleaning, as in that described previously, the length of the nozzle slot is made somewhat greater than would be necessary if the nozzles were exactly to follow the movements in question.

The machine cross-members provided for the yarn guide eyelets and nozzles are, as shown in Figure 1, simultaneously driven from a common shaft 16, suitable mechanism being provided to permit separate control of such members. Instead of mechanical coupling of this type, electrical coupling is also possible.

A particularly convenient structural arrangement is achieved when the machine cross-member provided for actuating the nozzles is itself moved backwards and forwards and the portions of the pneumatic equipment carrying the nozzles are entrained by the machine cross-member in its reciprocating movement. With this construction it is possible by simple means so to effect the connection between the nozzles and the machine cross-member which moves same backwards and forwards that the distance between the nozzles and the draw frame is easily adjustable and further that the nozzles can be swung out of their normal operating position, which is near to the delivery nip rollers. Such an arrangement substantially facilitates not only the overhaul and replacement of the nozzles, but also, when long-stapled material is being spun, the knotting of broken ends between the draw frame and the spindle. Typical embodiments in this connection are shown diagrammatically in Figs. 2 to 5 of the drawing.

Figures 2 and 3 illustrate a modification of the invention. In Figure 3 the nip rollers, the yarn guide eyelet 9 with its bracket 27, the machine cross-member 12 and the yarn filament 8 are omitted to obviate confusion. The collecting duct 59, which extends in Fig. 2 perpendicularly to the plane of the drawing and in Fig. 3 in the plane of drawing from top to bottom, is stationary. The nozzles 51 are mounted in groups on hollow cylinders 52 which in turn are connected by articulated conduits, as for example rubber tubes 53, to the stationary collecting duct 50. All the cylinders 52 of the spinning machine, Figs. 2 and 3 illustrating one cylinder, are secured by means of angle brackets 54 direct to the reciprocating machine cross-member 55. The movement of the machine cross-member 55 is participated in by the cylinders 52 and the nozzles 51 mounted thereon, as indicated by the positions 51', 55' and 52' of these parts shown by means of dotted lines in Fig. 3.

In Figs. 2 and 3, moreover, means are indicated by means of which the distance between the nozzles 51 and the fluted delivery rollers 3 of the draw frames may be adjusted independently of the reciprocating movement of the nozzles. For this purpose the cylinders 52 are mounted on the angle brackets 54 so as to be rotatable on axes parallel to the axes of the fluted rollers 3. By the rotation of the cylinders 52, the nozzles 51 are likewise rotated, so that the distance between the nozzles 51 and the fluted rollers 3 is adjustable between the limit positions 51 and 51'. The stop 56 serves to limit the swivelling movement of the nozzles. To facilitate knotting of broken threads, the nozzles 51 are swung away from the fluted rollers to the position 51' and, 75

when knotting up has been performed, restored to position 51. Said position 51' should be at least a finger's breadth further away from the fluted rollers 3 than the normal operating position 51 of the nozzles.

In the embodiment shown in Figs. 4 and 5, Fig. 4 shows an elevation in the axial direction of the draw frame and Fig. 5 a simplified view in plan in which the nip rollers 1 to 4, the yarn guide eyelets 9 with their brackets 27, and the machine cross-member 12 provided for the reciprocating movement of the yarn eyelets, are, for reasons of clarity, not shown. The yarn eyelets 9 (Fig. 4) which move the yarn 8 to and fro in the axial direction of the fluted rollers 1 and 3 are mounted on brackets 27 which are secured direct to the machine cross-member 12. The machine cross-member 60 provided for the actuation of the nozzles 61 is fitted directly below the cross-member 12, an arrangement which may prove advantageous for structural reasons in the case of two-unit draw frames. The two machine cross-members 12 and 60 are reciprocatingly moved, in Fig. 4, by means of actuating devices not shown, in a direction perpendicular to the plane of the drawing, and in Fig. 5 from top to bottom in the plane of the drawing. The dotted line 66' in Fig. 5 shows the amplitude of the reciprocating movement. All other parts shown in Fig. 1 of the device are omitted from Figs. 4 and 5.

Contrary to what is the case in Fig. 1, in Figs. 4 and 5 the collecting duct 62 is rigidly mounted in the machine frame. Each nozzle 61—in Fig. 5 only two such nozzles are shown—is mounted on its own nozzle-pipe 63 which is articulately connected to the collecting duct 62, by means, for instance, of a short length of rubber tube 64. Also secured to the machine cross-member 60 is, for each nozzle, a flat iron strip 65 provided with a slot 66 adapted to the diameter of the nozzle-pipe 63. Said slot is so dimensioned (Fig. 4) in the direction of normal pay-out of yarn 8' that on the one hand the nozzle-pipe 63 is prevented from bearing on the fluted roller 3 and on the other hand the nozzle 61 with its nozzle-pipe 63 is swingable away from the fluted roller 3 into the positions 61'' and 63'' indicated by dotted lines. The upper, normal operating position, indicated in plain lines, of the nozzles 61 is fixed by means of a spring 67 secured to the nozzle-pipe 63, which spring snaps into a recess provided on the flat iron strip 65. The position shown in dotted lines is that into which the nozzle is temporarily brought when broken ends have to be knotted. Thus each nozzle can, independently of the other nozzles and also independently of the joint reciprocating movement, be swung away from the corresponding fluted roller, so that when a broken end is being knotted the desired action of the other nozzles is not interrupted. For the rest, Fig. 4 shows the course of the yarn shortly after a yarn breakage. The yarn still continuously supplied by the draw frame is sucked up by the nozzle 61 and removed, whilst the broken-off section 8'' of the yarn continues to be taken up in the normal way by the spindle not shown.

I claim:

1. In combination with a spinning machine, draw frame rollers, yarn guide eyelets through which rovings are supplied to the rollers, means for reciprocating the eyelets at a predetermined cycle in the axial direction of the rollers, nozzles for removing by pneumatic suction dust, fluff, broken yarn ends and the like, the nozzles being

placed between the rollers and the spindles of the machine, and mechanism for reciprocating the nozzles in the axial direction of the rollers in a cycle differing from that of the reciprocating movement of the yarn guide eyelets.

2. In combination with a spinning frame, draw frame rollers, yarn guide eyelets through which rovings are supplied to the rollers, a machine cross-member connected to the eyelets, means for reciprocating the machine cross-member and connected eyelets in a predetermined cycle in the axial direction of the rollers, a movable second machine cross-member extending axially of the draw frame rollers, nozzles moved by said second machine cross-member for removing by pneumatic suction dust, fluff, broken yarn ends and the like, the nozzles being placed between the rollers and the spindles of the machine, and means for reciprocating the second machine cross-member in the axial direction of the rollers in a cycle differing from that of the reciprocating movement of the yarn guide eyelets.

3. A spinning machine according to claim 2 including a device to adjust the amplitude of the reciprocating movement of the nozzles in relation to that of the reciprocating movement of the yarn guide eyelets.

4. A spinning machine according to claim 3 including a device for adjusting the phase position of the reciprocating movement of the nozzles in relation to that of the reciprocating movement of the yarn guide eyelets.

5. In combination with a spinning frame, draw frame rollers, yarn guide eyelets through which rovings are supplied to the rollers, a machine cross-member connected to the eyelets, means for reciprocating the machine cross-member and eyelets in a predetermined cycle in the axial direction of the rollers, a second machine cross-member, a duct moved by said second machine cross-member, nozzles in said duct for removing by pneumatic suction dust, fluff, broken yarn ends and the like, the nozzles being placed between the rollers and the spindles of the machine, and means for moving the second machine cross-member and the duct carrying the nozzles backwards and forwards in the axial direction of the rollers in a cycle differing from that of the reciprocating movement of the yarn guide eyelets.

6. In combination with a spinning machine, draw frame rollers, yarn guide eyelets through which rovings are supplied to the rollers, means for reciprocating the eyelets in a predetermined cycle in the axial direction of the rollers, a plurality of nozzles for removing by pneumatic suc-

tion dust, fluff, broken yarn ends and the like, the nozzles being placed between the rollers and the spindles of the machine, a fixed collecting duct, nozzle-pipes connecting each nozzle with the collecting duct, a machine cross-member connected to the nozzle-pipes, and means for reciprocating the machine cross-member in the axial direction of the rollers thereby reciprocating the connected nozzles.

10 7. A spinning machine according to claim 6 including a device in which the machine cross-member carries a strip having a slot through which the nozzle-pipe extends, the nozzle-pipe being movable in a vertical direction in said slot, and a flexible member for securing the nozzle-pipe in place in said slot.

15 8. A device according to claim 6 characterized by the fact that means are provided to permit adjustment of the distance separating the nozzles from the nip rollers on the delivery side of the draw frame approximately in the direction of the yarn being paid out.

9. A spinning machine according to claim 8 characterized by the fact that in normal operation the nozzles are moved backwards and forwards adjacent the delivery nip rollers of the draw frames, and that the means to permit adjusting the distance between the nozzles and the rollers are such as to permit the nozzles being swung away from the delivery of the nip rollers by at least the breadth of a finger.

10 10. In combination with a spinning frame, draw frame rollers, yarn guide eyelets through which rovings are supplied to the rollers, a machine cross-member connected to the eyelets, means for reciprocating the machine cross-member and eyelets in a predetermined cycle in the axial direction of the rollers, a second machine cross-member, a plurality of ducts moved by said second machine cross-member, nozzles arranged in groups on said ducts for removing by pneumatic suction dust, fluff, broken yarn ends and the like, a collecting duct, flexible lines connecting the nozzle ducts to the collecting ducts, the nozzles being placed between the rollers and the spindles of the machine, and means for moving the second machine cross-member and the ducts carrying the nozzles backwards and forwards in the axial direction of the rollers.
